The ornamental design for a compartmentalized fishing pole and accessory carrier, as shown and described.

DESCRIPTION

FIG. 1 is a perspective view of a compartmentalized fishing pole and accessory carrier in a closed configuration showing my new design therefor. The broken line drawing depicting a fishing rod and reel is for purposes of illustration only and forms no part of my design;

FIG. 2 is a perspective view;

FIG. 3 is a front elevational view;

FIG. 4 is a rear elevational view;

FIG. 5 is a left side elevational view, the right side elevational view being a mirror image thereof;

FIG. 6 is a top plan view; and,

FIG. 7 is a bottom plan view.
